UNITED STATES PATENT OFFICE.

JOHN W. WOOD, OF WESTON, MISSOURI.

BABY-WALKER.

SPECIFICATION forming part of Letters Patent No. 509,991, dated December 5, 1893.

Application filed June 10, 1893. Serial No. 477,136. (No model.)

To all whom it may concern:

Be it known that I, JOHN W. WOOD, of Weston, Platte county, Missouri, have invented certain new and useful Improvements 5 in Baby-Walkers, of which the following is a full, clear, and exact description, reference being had to the accompanying drawings, forming a part hereof.

My invention relates to improvements in 10 that class of devices, whereby a baby or child too weak or young for walking may be safely supported, and at the same time may be enabled to move to any part of the room; furthermore a device of this character which is 15 simple, strong, durable and inexpensive of construction.

With these objects in view my invention consists in certain peculiar and novel features of construction and combination of parts as 20 will be hereinafter described and claimed.

In order that my invention may be fully understood, I will proceed to describe it with reference to the accompanying drawings, in which—

25 Figure 1, is a plan view of the device constructed in accordance with my invention. Fig. 2, is a vertical sectional view taken on the line $x-x$ of Fig. 1. Fig. 3, is a detail perspective view of one corner of the device, to 30 show more clearly the construction thereof.

In the drawings, a rectangular frame is composed of the bars or rods 1; these bars or rods being firmly secured together in any suitable manner, so as to form the extensions 1^a projecting beyond the body portion of the rectangular frame. A top plate or board 2 is arranged horizontally, and is secured in any suitable manner upon said framework, and is formed with a central and circular hole or 35 opening 3. A rectangular framework similar to the framework composed of the bars or rods 1 but on a larger scale is formed of the bars 4, and this framework is also provided with extensions 4^a projecting beyond the 40 body portion thereof and in a manner similar to the extensions 1^a. This framework is arranged horizontally beneath the frame work composed of the bars 1 a suitable distance, and the sides thereof extend parallel with the 45 sides of said first mentioned framework.

Secured at their upper ends by screws or other suitable means to the adjacent and

outer vertical sides of each pair of extensions 1^a are the downwardly diverging and similar guard-bars 5. A pair of these bars 5 depend 55 from each corner of the rectangular framework, and are secured a suitable distance from their lower ends to the outer vertical sides of the extensions 4^a of the lower rectangular frame-work. The lower portions of 60 these bars 5 are formed each with a longitudinally extending slot 6, and an arm or bar 7 has a tongue or pin 8 projecting into said slots, and near its upper end has a bolt 8^a which passes through and is adapted to operate in the slot of the bars 5. A clamping nut 9 is adapted to engage the projecting ends of each bolt 8^a to secure the arms or bars at any point of adjustment relative to the bars 5. By arranging the guard-bars 5 so as to project divergently downward and have their lower ends, or the lower ends of their extension arms or bars, adjacent to the floor, it will be seen that it will be impossible for the child therein to tip or turn the device over. 75

A horizontally arranged guide plate 10 is secured to the adjacent sides of each pair of corner bars 5, and is formed with a vertical guide opening through which the vertical rod 11 passes. This vertical rod 11 also passes 80 through a guide opening formed through the lower rectangular frame at the junction or crossing point of the bars 4. A collar 11^a fitting upon the cylindrical rod 11 below the guide bracket 10 is adjustable by means of 85 the set screw, and a similar collar 11^b fitting upon the cylindrical rod 11 above the lower frame is also adjustable by means of the set screw. By operating its set screw, the collar 11^a may be moved downward upon the 90 rods 11, which will allow the frame-work consisting of the upper and lower horizontal frames and the connecting bars 5 to move downward a corresponding distance until the guide brackets 10 rest upon the collars 11^a. 95 By operating the set-screw of the collar 11^b the frame-work referred to may be lifted or raised upward upon the rods 11 any suitable distance, and by moving and securing the collars 11^a to and against the under side of 100 the guide brackets 10 the framework may be supported in said position, the collar 11^b being adapted to limit the upward movement of the framework. The arrangement of the

collars 11^a and 11^b allows the structure to be adjusted to different heights.

Secured revolvably upon the lower ends of the rods 11 are the brackets 12, which are formed with a pair of parallel ears or extensions between which is journaled a caster roller 13 in the usual manner. Secured to the under side of the upper frame-work, are the cross bars 14; these cross bars forming a rectangular frame-work similar to the one formed by the cross-bars 1. Projecting inwardly from the inner vertical side of each cross bar 14 is a pin or bolt 15, and mounted to revolve thereon are rollers 16. An annulus or ring 17 of diameter about equal to the opening 3 of the top plate or board 2 is formed at its upper margin with an outwardly projecting horizontal annular flange 18, and this flange is fitted beneath the under side of the top plate or board, and rests upon the rollers 16. It will thus be seen that this annulus or ring may be easily revolved to any point desired. A seat is formed of a body-portion 19 of approximately semi-circular form, and arms 20 projecting laterally from the front end of said body-portion.

Projecting rearwardly and at right angles preferably to the arms 20 are the extensions or arms 21; these extensions or arms being formed integral with the arms 20 or secured thereto as desired, and form the spaces 22 at opposite sides of the body-portion 19 of the seat, the object of which will be hereinafter explained. Secured to the rear ends of the arms or extensions 21 are the lower ends of the straps 23, and secured at their upper ends to clips 24 carried by the annulus or ring 17 are straps 23^a which are provided with buckles 25 at their lower ends, which are adapted to be engaged by the upper or free end of the straps 23. Secured to the outer ends of the arms 20 are the lower ends of straps 26, and secured at their upper ends to clips carried by the annulus or ring 17 are straps 26^a which are provided with buckles 28 at their lower ends, and these buckles are adapted to be engaged by the upper ends of the straps 26. A flexible connection 29 preferably of rubber tubing, has its upper end passed through a clip or ring 30 carried by the annulus, and has its end turned down and wrapped to the body portion of the tubing by a cord or other suitable means, so that it may be adjusted easily when desired. The lower end of this tubing 29 is secured in any suitable manner to the under side and about the middle of the body portion of the seat. It will thus be seen that this construction provides a yielding support for the child, who is adapted to be placed upon the seat so that his limbs shall be astride of the rubber tubing 29, and so that the rear and side portions of the dress or garments may hang freely in the spaces 22 at the sides of the body-portion of the seat and also to the rear thereof so as not to crumple or disarrange them. The seat is also adapted to be adjusted a suitable dis-

tance from the floor so that the feet of the child may reach the same, and this is accomplished by adjusting the collars 11^a, and 11^b, 70 as before explained.

In order to provide a support for the head, a U-shaped clip or frame 32 is provided, and the forward ends of this clip or frame are formed with the vertical and depending extensions 33 which engage the vertical clips or retainers 34 secured to the inner side of the annulus in rear of the seat. A flexible connection or strap 35 is formed with loops in its opposite ends which are slipped upon 80 said U-frame, and arranged to extend from one arm of the frame to the other, and parallel with the front margin of the seat. It will thus be seen that should the child turn, the annulus and seat will also turn, and the 85 flexible strap or support 35 will always be presented and adapted to receive the head should the child move rearwardly, and prevent its contact with the annulus or the edge of the opening 3 of the top plate or board. 90

The operation of this device will be readily understood, the child by simply pushing with its feet against the floor moving the device to any part of the room desired, and by simply turning its body the annulus or ring will be 95 revolved so that the child may face in any direction.

This device is peculiarly well adapted in cases where the parents wish the child to learn to walk or rather to learn to step, as the 100 device will readily move by the stepping action of the feet upon the floor, without learning to crawl, and thus obviating the necessity of a person to constantly watch or keep an eye on the child to prevent it getting into 105 danger or mischief.

From the above description, it will be seen that I have produced a baby walker or device of the character described which is simple, strong, durable and inexpensive of construction, which may be adjusted to suit children of different heights or sizes, and which it will be impossible for the child to topple over by reason of the guard-bars 5, which or rather the extensions thereof extend to within a slight distance of the floor and outward of the rollers 13, and which therefore would contact with the floor should the device be tilted a slight distance. 115

Having thus described my invention, what 120 I claim as new, and desire to secure by Letters Patent, is—

1. In a baby-walker, the combination of a frame work mounted upon rollers, and a seat carried by said framework, of a series of downwardly divergent guard-bars secured to the framework, and adapted to prevent the accidental toppling or turning over of the device, substantially as set forth.

2. A baby walker, comprising a suitable 130 frame-work mounted upon rollers, an annulus or ring revolvably mounted in said frame-work, a seat adjustably suspended from said annulus or ring and adapted to turn therewith, and

a head supporting frame consisting of a frame secured to the annulus, and a band carried by said frame, substantially as and for the purpose set forth.

5 3. A baby walker, comprising a suitable frame-work, vertical rods adjustably carried by said frame-work, and rollers carried at the lower ends of said rods, a seat adjustably supported from said framework, and guard-bars carried by said frame-work, and adjustable bars carried upon the lower ends of said guard-bars, and means to hold said adjustable bars at any desired point of adjustment, substantially as set forth.

15 4. A baby walker, comprising a series of vertical rods, a suitable frame-work adjustably mounted upon said rods, in combination with an annulus revolvably mounted within said frame-work, and a seat yieldingly supported by said annulus, and a head rest or support carried by said annulus, and a yield-

ing strap carried by said head support, substantially as and for the purpose set forth.

5. A baby walker, comprising a suitable frame-work mounted upon rollers, a top plate 25 or board supported upon said frame-work, rollers supported by said frame-work, and an annulus or ring having an outwardly extending flange extending under the top plate or board and resting upon the said rollers, and 30 a seat yieldingly supported by the annulus or ring, and having its body portion approximately semicircular, and a yielding head support carried by the annulus or ring, all arranged as described, substantially as and for 35 the purpose set forth.

In testimony whereof I affix my signature in the presence of two witnesses.

JOHN W. WOOD.
